THERMOSTATIC VALVE

Arthur J. Schutt, Lockport, N. Y., assignor to
 General Motors Corporation, Detroit, Mich., a
 corporation of Delaware

Application November 21, 1934, Serial No. 754,034

1 Claim. (Cl. 236—34)

This invention relates to valves for use at the junctions of three conduits to direct into either of two of the conduits fluid flowing toward the junction through the third and, particularly, to valves for use in the cooling systems of internal combustion engines to determine whether the water which is discharged from the engine water jacket shall flow through the radiator before it is returned to the water jacket.

10 The invention resides in cooperating elements which can, as units, be united with and separated from each other and are so constructed and arranged that a valve element which constitutes a part of one of them is capable of being moved from a position in which it directs fluid into one path to a position in which it directs the fluid into another path. The invention further comprehends the inclusion in the element of which the valve element constitutes a part of a thermosensitive element through which the position of the valve element is regulated in accordance with the temperature of the fluid.

For a better understanding of the nature and objects of the present invention, reference is made to the following specification, wherein there is described the preferred embodiment of the invention which is illustrated in the accompanying drawing.

In the accompanying drawing:

20 Figure 1 is a fragmentary view of a water cooled internal combustion engine in whose cooling system there is installed a valve in accordance with this invention.

Figure 2 is a section taken on the line 5—5 of Figure 1.

In Figure 1, the reference character 10 indicates a water cooled internal combustion engine and the reference character 11 a radiator, whose upper and lower tanks 12 and 13 are connected by a core 14 in which there are provided water cooling passages between which the engine operated fan 15 is adapted to draw air. The lower tank 13 of the radiator 11 is connected to the water jacket of the engine 10 by a conduit 16 in which there is installed an engine operated water pump which is not shown in the drawing.

The outlet fitting 47 which is secured over an opening in the upper wall of the water jacket of the engine is of conventional design; but, within the upper tank 12 of the radiator 11 of the engine, there is located a fitting 38 which consists of a base 39 in which there are provided openings 40 and 42 which register, respectively, with openings in the rear wall 51 of the tank and a hollow arm 44 which extends from the opening 42 to a

point opposite the opening 40. Through the wall of the hollow arm 44 which faces the opening 40, there extends a circular opening 52 which is coaxial with the opening 40, and on the inner wall of the hollow arm 44 opposite the opening 52 there is formed a flat-faced boss 53. Without the tank 12, there is located a fitting 41 on which there are formed a tubular boss 43 which registers with the opening 40 in the fitting 38 and is connected to the outlet fitting 47 by a conduit 48 and a tubular boss 46 which registers with the opening 42 in the fitting 38 and is connected to the conduit 16 by a conduit 49.

The reference character 26 indicates a unit which includes an annular element 27 whose outer edge is clamped between the fittings 38 and 41 by the screws 45 which secure the fittings together and to the rear wall of the tank 12 and on whose inner edge there is formed an upward cylindrical flange 35. To the annular element 27, there are secured the extremities of the legs of a stirrup-like element 28 which extends into the tubular boss 43. To the base of the stirrup 28, there is secured one end of a metal bellows 29 which is filled with a volatile liquid. To the free end of the bellows 29, through the intermediary of a stem 30 and a fork 31 which extends through the opening in the annular element 27, there is secured a valve element 32 which is located on the side of the annular element 27 opposite that on which the bellows and the stirrup are located. The valve element 32 is shaped generally like a sombrero from which the top of the crown has been removed and includes an annular portion 33 and a cylindrical portion 34 whose lower end merges into the inner edge of the annular portion and whose upper end fits somewhat loosely in the opening 52 in the hollow arm 44 of the fitting 38. The annular portion 33 seats on the cylindrical flange 35 on the annular element 27 when the bellows 29 is collapsed, and the outer end of tubular portion 34 seats on the boss 53 on the inner wall of the hollow arm 44 when the bellows is expanded.

It will be apparent that water which is forced by the pump into the water jacket of the engine 10 and thence through the outlet fitting 47 and the conduit 48 into the tubular boss 43 of the fitting 41 may leave the latter either between the flange 35 of the annular element 27 and the annular portion 33 of the valve element 32 or through the tubular portion 34 of the valve 32 and the fitting 38. Water which leaves the tubular boss 43 between the flange 35 of the annular element 27 and the annular portion 33 of the

valve element 32 passes through the radiator 11 and is, consequently, cooled before it is drawn into the conduit 16 by the pump and returned to the water jacket. Water which leaves the tubular boss 30 through the tubular portion 34 of the valve 32 and the fitting 38 passes through the conduit 49 instead of the radiator and, consequently, is not considerably cooled before it is drawn into the conduit 16 by the pump and returned to the water jacket. Whether water which leaves the water jacket is returned thereto by way of the radiator 11 or by way of the conduit 49 depends upon the temperature of the water in the water jacket, since the position of the valve element 32 is controlled by the bellows 29 which expands when it is heated and contracts when it is cooled. When the temperature of the water in the water jacket is low as it normally is when the engine is started, the bellows will be contracted and the valve element will occupy the position in which it is shown in solid lines in Figure 2, in which the annular portion thereof is seated on the flange 35 of the annular element 27 and the outer end of the cylindrical portion thereof is out of contact with the boss 53 in the hollow arm of the fitting 38. When the valve element is in this position, no water can leave the tubular boss 43 except by way of the tubular portion 34 of the valve 32 and the fitting 38 and, consequently, the water which leaves the water jacket will not be considerably cooled before it is returned thereto. When the temperature of the water in the water jacket is high, as it normally is during operation of the engine, the bellows will be expanded and the valve element 32 will occupy the position in which it is shown in dash-and-dot lines in Figure 2 in which the outer end of the cylindrical portion thereof is seated throughout its circumference on the boss 53 and the annular portion thereof is out of contact with the cylindrical flange 35. When the valve element is in this position, no water can

pass through the tubular portion 34 of the valve 32 and, consequently, the water which leaves the tubular boss 43 will pass between the flange 35 of the annular element 27 and the annular portion 33 of the valve 32 and into the radiator 11 and be cooled before it is returned to the water jacket. Of course, when the temperature of the water in the water jacket is such that the valve element is positioned between the two extremes which have been considered, the water which leaves the tubular boss 43 will be returned to it partly by way of the radiator and partly by way of the conduit 49.

In concluding this specification, it is perhaps worth while to call attention to the fact that the unit 26 is, as a unit, separable from the parts with which it is associated after the fitting 41 has been disconnected from the rear wall of the upper tank of the radiator 11; and that the valve herein disclosed may be employed at the junction of three conduits to regulate the flow of fluid from two of the conduits into the third as well as in the manner illustrated and described.

I claim:

In an internal combustion engine, a member in which there is provided an opening, a valve element which includes a generally tubular portion through which fluid may pass and is adapted to cooperate with the member to prevent flow of fluid through the opening therein except by way of the generally tubular portion, a temperature responsive actuating element carried by the mentioned member and connected to the valve element, a radiator in which there is included a tank with a ported wall, two ported members between which the ported wall of the tank and the first mentioned member are clamped, and a conduit carried by the ported member within the tank and telescopically related to the tubular portion of the valve element.

ARTHUR J. SCHUTT.
